UNITED STATES PATENT OFFICE.

WALTER REES, OF YORK, PENNSYLVANIA.

CHANGEABLE KEY-LOCK.

1,004,904.

Specification of Letters Patent.

Patented Oct. 3, 1911.

Application filed October 26, 1910. Serial No. 589,121.

To all whom it may concern:

Be it known that I, WALTER REES, of York, in the State of Pennsylvania, have invented a certain new and useful Improvement in Changeable Key-Locks, whereof the following is a specification, reference being had to the accompanying drawings.

It is the usual practice of lessors of safety deposit boxes to provide them with locks which may be opened with keys furnished to the lessees, and, upon the termination of any lease of a given box to provide it with a new lock to insure that the former lessee has not a duplicate key with which the box may be opened after it has been leased to another person. Moreover, when it is desired to require the presence or consent of two persons to open such a box, it is usual to provide it with a lock having in addition to the mechanism subject to the control of a main key by which the lock slide bolt is shifted back and forth, guard or detent mechanism, subject to the control of a guard key, so constructed and arranged as to prevent the operation of the lock by the main key until said detent mechanism is released by the operation of the guard key.

My invention relates to a lock which may be advantageously used for the special purposes aforesaid in that it may be manually changed to be operated by different main keys of a numerous series, without being detached from such a box, and includes detent mechanism, having two independent functions, subject to the control of a master guard key, to wit, first, preventing or permitting such changes in the lock, and, second, preventing or permitting the operation of the lock by the specific main key for which it is set. In other words, a lock constructed in accordance with my invention as herein-after described is normally subject to control by two keys, to wit, any selected main key of a numerous series, whereby the slide bolt may be shifted back and forth when the detent mechanism is released, and, a master guard key capable of releasing said detent mechanism. However, said two functions of said detent mechanism being performed by independent means may be independently controlled by different guard keys, herein-after respectively designated a "change" guard key and a "release" guard key. Moreover, one of said independent detent means may be omitted to permit the

lock to be repeatedly opened by the main key without the repeated operation of the guard key.

As hereinafter described, my invention includes a lock of the "Yale" type having a main rotary plug, with a keyway and a straight series of radial pin tumbler sockets; two straight series of pin tumbler sockets in the lock casing, arranged to respectively register with the sockets in said main plug in different rotary positions of the latter; said main rotary plug being arranged to normally coöperate with pin tumblers in but one of said series of sockets in the casing; changeable divisional unit pin tumblers in said sockets, all of the same length, whereby said lock is changeable to be operated by any one of a plurality of keys having notches the depths of which bear aliquot relation to said tumbler sections; detent mechanism arranged to normally limit the rotary movement of said main plug to register with the main series of casing sockets but to abnormally permit rotary movement of said plug to register with the other series of casing sockets, and to normally prevent the opening movement of the slide bolt but abnormally permit such movement; and, a rotary guide plug having a keyway and a single straight series of radial pin tumbler sockets, constructed and arranged to control and operate said detent mechanism in accordance with its rotary position.

My invention includes the various novel features of construction and arrangement herein-after more definitely specified.

In said drawings; Figure I is a front view of a lock conveniently embodying my invention. Fig. II is an inverted plan sectional view of said lock, taken on the line II, II in Figs. I and III, showing a master guard key. Fig. III is a vertical transverse sectional view of said lock, taken on the line III, III in Figs. I, II, and VI. Figs. IV, V and VI are vertical longitudinal sectional views of said lock, taken on the line VI, VI in Figs. II and III; Fig. VI showing the lock mechanism in the position in which it appears in Figs. I, II and III, and, Figs. IV and V showing said mechanism in other positions. Fig. VII is a sectional view, taken on the line VII, VII in Figs. II and III. Fig. VIII is a longitudinal sectional view of said lock, taken on the line VIII, VIII in Fig. IX, showing a release guard

key. Fig. IX is an inverted plan sectional view of said lock, taken on the line IX, IX in Fig. VIII. Fig. X is a fragmentary sectional view taken on the line X in Fig. IX. 5 Fig. XI is like Fig. X, but shows a modified form of my invention.

In said figures; the lock casing 1 has the removable face plate 2 detachably connected by the screws 3 with the casing frame 4. The main rotary plug 6 having the keyway 7 for the main key 8, and the series of radial pin tumbler sockets 9, is journaled in said frame 4 in which it is retained at the front end by the circumferential flange 11 10 having the notches 12 and 13 to permit said key 8 to be inserted and withdrawn in the respectively locked and unlocked positions of said plug 6; said flange 11 being fitted to the notch 15 in said key so that the latter 15 must be inserted to the full extent indicated 20 in Fig. II before it or said plug 6 may be turned in said frame 4. As shown in Fig. III said plug 6 has the crank stud 17 at its inner end which fits in the slot 18 in the shank 19 of the slide bolt 20 as shown in 25 Fig. VI, so that said bolt may be shifted back and forth by the rotation of said plug 6. Said slide bolt 20 has the slot 21 engaging the stud 22 on the slide plate 23 which 30 as shown in Figs. II and VII is arranged to slide in the frame 4 transversely with respect to the direction of motion of said slide bolt 20 and has the spline 25 fitted to slide in said frame 4 to maintain it in proper 35 position in said frame. It may be observed that said slide bolt 20 cannot be shifted in either direction unless said slide plate 23 is free to move in said frame 4, and, as shown in Figs. II and VII said slide plate 23 has 40 the straight series of tumbler bearings 26 containing the pin tumbler sections 27 by which it may be engaged with the frame 4 and the slide bolt 20 be thus maintained stationary in the locked position shown in 45 Figs. I, II, III, VI and VII. The pin tumbler sections 28 in said sockets 9 of the main rotary plug 6 are rounded at their inner ends so as to readily slip into and out of the angular notches 29 in the main keys 50 8. The length of each of said tumbler sections 28 equals the radial thickness of said rotary plug 6 beyond the keyway 7, and the extent of said plug sockets 9 radially beyond said tumbler sections 28 is filled by the 55 changeable unit pin tumbler sections 30 which are each as long as the minimum difference in depth of said key notches 29, and, as shown in Fig. II said sockets 9 are filled to the radial extent of the plug 6 with 60 different numbers of said changeable pin tumbler sections 30 in accordance with the different key notches 29. Said frame 4 has the straight series of main pin tumbler sockets 32 which register with said bearings 26 and the pin tumblers 27 when the

slide plate 23 is in locked position as shown in Figs. II and VII. Said sockets 32 contain pin tumbler driver sections 34 which are pressed toward the rotary plug 6 by respective springs 35 so that when the proper key 8 is inserted in the keyway 7 as shown in Fig. II, the tumbler sections 27 which extend in the bearings 26 of the slide plate 23 and are coextensive with the thickness of the latter, do not project from said plate, 70 and the latter may be shifted back and forth by engagement in the cam slot 21 in the bolt shank 19 as the latter is shifted back and forth by the crank stud 17 on the main rotary plug 6, as the latter is turned 75 by the key. However, when said key 8 is withdrawn with the bolt 20 and slide plate 23 in said locked position as shown in Fig. II, said springs 35 shift the pin tumblers 34 and 27 toward the plug 6 to engage the 80 slide plate 23 and said plug 6 in the frame 4 and prevent their unlocking movement. Thereafter, it is impossible to unlock the bolt 20, except when the proper key 8 is inserted in the keyway 7 of the main rotary 85 plug 6; because a key having different notches 29 causes the tumbler sections 27 to project from the slide plate 23 and thus prevent its movement. Moreover, as shown in Fig. VI the unlocking movement of said 90 slide bolt 20 is normally prevented by the detent 37 which engages the bolt shank in its protracted locked position. Said detent is conveniently a lever fulcrumed on the stud 38 and having the spring 39 tending to 95 present it in engagement with the shank 19 of said bolt 20. However, said detent 37 is subject to the control of the guard 100 rotary plug 40 having the keyway 41 for the master key 42, and the series of radial pin 105 tumbler sockets 43. Said plug 40 is journaled in said frame 4 in which it is retained at the front end by the circumferential flange 45 having the notch 46 to permit said key 42 to be inserted and withdrawn when 110 said plug 40 is in the position shown in Figs. I, II and VI; said flange 45 being fitted to the notch 48 in said key 42 so that the latter must be inserted to the full extent indicated in Fig. II before it or said 115 plug 40 may be turned in said frame 4. It may be observed that when said plug 40 is turned to the position shown in Fig. VI, which is the normal position, said detent 37 is free to prevent the unlocking movement 120 of the bolt 20, and, said plug 40 must be turned by the guard key 42 to the abnormal position shown in Fig. V, so that the cam 49 at the inner end of said plug 40 releases said detent 37 from engagement with the shank 125 19 of said bolt, against the pressure of said spring 39, to permit the opening movement of said bolt 20, by the key 8.

The pin tumbler sections 51 in the guard rotary plug 40 are rounded at their inner 130

ends so as to readily slip into and out of the angular notches 52 in the guard key 42. The length of each of said tumbler sections 51 conveniently equals the radial thickness 5 of said plug 40 from the bottom of its respective key notch 52 to the periphery of said plug, and, in the normal position of said plug shown in Fig. II the tumbler sockets 43 and the tumblers 51 in said plug 40 10 register with the straight series of auxiliary tumbler sockets 54 in the frame 4. Said sockets 54 contain pin tumbler driver sections 55 which are pressed toward the rotary plug 40 by respective springs 56 so that when the proper guard key 42 is inserted in the keyway 41 in said plug 40 as 15 shown in Fig. II, the latter is free to turn, but, when said key 42 is withdrawn or any other key with different notches is inserted 20 in said plug 40 the latter is prevented from turning by the pin tumbler driver sections 55 which project in the sockets 43 in said plug.

Referring to Fig. II it may be observed 25 that when the deepest notches in the key 8 permit the sections 28 to assume their innermost position, but three of the changeable tumbler sections 30 are required to fill the sockets 9 to the radial extent of the plug 6. 30 However, four such sections are provided for each notch in the key 8, the extra ones always remaining in said auxiliary sockets 54 as drivers for the other sections 30 which are stored therein under pressure of said 35 springs 55.

The sole function of said detent 37 being to normally engage and detain the slide bolt 20 in its protracted, locked position; the normal extent of the unlocking movement of 40 said slide bolt 20 is limited by the detent 58 when in the position shown in Figs. V and VI so that said main rotary plug 6 is normally prevented from turning far enough to present its pin sockets 9 in registry with said auxiliary sockets 54 in said frame. Said detent 58 thus normally prevents a change of key. However, said detent 58 45 being conveniently a lever fulcrumed on the stud 59 and having the spring 60 tending to present it in engagement with the shank 19 of said bolt 20, as shown in Fig. V, is subject to the control of the guard rotary plug 40 which must be turned by the guard key 42 to the abnormal position shown in 50 Fig. IV, wherein the cam 49 on said plug 40 releases said detent 58 from engagement with the shank 19 of said bolt 20 against the pressure of said spring 60 to permit the 55 turning movement of said main rotary plug 6 to the position shown in Fig. IV to present its sockets 9 in registry with said auxiliary sockets 54 and thus permit a change of key. Said plug 6 being thus turned with the main key 8 to register with said auxiliary sockets, said key may then be with-

drawn, and, a new main key with different notches 29 being inserted in said plug, its notches are filled with the changeable tumbler sections 30, from said auxiliary sockets 54, to the radial extent of said plug 6, and, 70 the latter being returned to the normal position and the detent 58 replaced, the lock is thus set for operation by said new main key.

It is to be understood that the number of different main keys to which such a lock 75 may be thus set is only limited by the permutability of the tumbler sections 30, which bear an aliquot relation to the depth of the notches 29 in all of said series of main keys.

The form of my invention above described 80 operates as follows:—The lock being set for the main key 8 to present the tumblers 27 in the position shown in Fig. II; and, the master guard key 42 being inserted as shown in Fig. II and the lock being in the normal 85 locked position shown in Figs. I, II, III, VI and VII may be unlocked by first turning the guard plug 40 with said key 42 to the position shown in Fig. V and then turning the main rotary plug 6 with the main key 90 8 to the position shown in Fig. V. If the guard plug 40 is then returned with the guard key 42 to the normal position shown in Fig. VI, before said key 42 is withdrawn; upon returning the slide bolt 20 to 95 the locked position shown in Fig. II it cannot be again unlocked until said guard plug is first turned as above described. However, said detent 37 may be omitted to permit the lock to be repeatedly opened by the main 100 key 8 without the repeated use of any guard key. In other words, the embodiment of my invention shown and described may be instantly changed from a double key lock to a single key lock by merely omitting said 105 detent 37 without disturbing any other portion of the lock. This feature of my invention is obviously advantageous when it is desired to temporarily permit one person to open a safety deposit box to open which the 110 presence or consent of two persons is normally required.

In the operation above described the person having the master guard key 42 would have control of both of the aforesaid functions of the detent mechanism, to wit, first, preventing or permitting such changes in the lock tumblers as to adapt the lock to be opened by different main keys, and, second, preventing or permitting the operation of 115 the lock by the specific main key for which it is set. However, under some circumstances, it is desirable to have said two functions controlled by different persons provided with respectively different keys, and, 120 as said two functions of said detent mechanism are performed by independent means, to wit, the detents 37 and 58; the guard mechanism in the lock which I have shown is rendered capable of such independent 125 130

manipulation as to said two detent means by two keys respectively designated a change guard key and a release guard key. Such operation may be conveniently effected by 5 providing the guard plug 40 with peripheral recesses 62 and 63 which are indicated in Figs. II, VII, VIII and IX and which extend circumferentially upon respectively opposite sides of different tumbler sockets 10 43 in said plug as indicated in Figs. VII and VIII; so that when the tumbler sections 55 are thrust from the plug 40 to the circumference of the latter by the master guard key 42 as shown in Fig. II said plug 15 may be turned in either direction to operate either of said detents 37 and 38, but, when said tumbler sections 55 are thrust to the position shown in Fig. IX by the release guard key 65 one of said sections 55 engages 20 said plug to the depth of the recess 62 so that, although said plug may be turned by said release guard key in the direction indicated by the arrow in Fig. VIII to release the slide bolt shank 19 from the detent 37, 25 by the cam 49 of said plug 40, to permit the opening movement of said slide bolt 20; said guard plug 40 cannot be turned in the opposite direction because of the engagement of said tumbler section 55 therewith. 30 On the other hand, by the insertion of the change guard key 66 indicated in Fig. X all of the tumbler sections 55 are thrust outwardly from the plug 40 to the circumference thereof except the one which engages 35 said plug to the depth of the recess 63, so that said plug may be rotated in the direction of the arrow shown in Fig. X to shift the detent 58 to inoperative position by said cam 49, but, said plug 40 cannot be turned 40 in the opposite direction to operate said detent 37.

Although I find it convenient to form the recesses extending circumferentially from the sockets 43 in the plug 40 as shown in 45 Figs. VIII and X; they may be otherwise formed, for instance as indicated at 67 in Fig. XI. Said recess 67 extends at right angles to the axis of the socket 43, and, it may be observed that although such construction, of said recess 67, is less costly, the local tumbler section 55 is moved by the plug 40 as the latter is turned and may be worn unevenly upon its end which comes in contact with said plug.

55 I do not desire to limit myself to the precise details of construction and arrangement herein shown as it is obvious that various modifications may be made therein without departing from the essential features of my 60 invention as defined in the appended claims.

I claim:

1. In a changeable key lock, the combination with a casing; of a main rotary plug, having a keyway and a straight series of 65 radial pin tumbler sockets; two straight se-

ries of pin tumbler sockets in said casing, arranged to respectively register with the sockets in said main plug in different rotary positions of the latter; pin tumblers including changeable unit sections in said sockets, 70 all of the same length, whereby said lock is changeable to be operated by any one of a plurality of keys having notches the depths of which bear aliquot relation to said changeable tumbler sections; detent mechanism arranged to normally limit the rotary movement of said main plug to register with the main series of casing sockets but to abnormally permit rotary movement of said plug to register with the other series of 80 casing sockets, and, to normally prevent the opening movement of the slide bolt but abnormally permit such movement; and, a guard rotary plug having a keyway, a single straight series of radial pin tumbler 85 sockets and pin tumblers, constructed and arranged to control and operate said detent mechanism.

2. In a changeable key lock, the combination with a casing; of a main rotary plug, 90 having a keyway and a pin tumbler socket; two pin tumbler sockets in said casing, arranged to respectively register with the socket in said main plug in different rotary positions of the latter; pin tumblers including changeable unit sections in said sockets, 95 all of the same length, whereby said lock is changeable to be operated by any one of a plurality of keys having notches the depths of which bear aliquot relation to said changeable tumbler sections; detent mechanism arranged to normally limit the rotary movement of said main plug to register with the main casing socket but to abnormally permit rotary movement of said plug to 100 register with the other casing socket, and, to normally prevent the opening movement of the slide bolt but abnormally permit such movement; and, a guard rotary plug having a keyway, a pin tumbler socket and a 105 pin tumbler, constructed and arranged to control and operate said detent mechanism.

3. In a changeable key lock, the combination with a casing; of a main rotary plug, having a keyway and a pin tumbler socket; 115 two pin tumbler sockets in said casing, arranged to respectively register with the socket in said main plug in different rotary positions of the latter; pin tumblers including changeable unit sections in said sockets, 120 all of the same length, whereby said lock is changeable to be operated by any one of a plurality of keys having notches the depths of which bear aliquot relation to said changeable tumbler sections; detent mechanism arranged to normally limit the rotary movement of said main plug to register with the main casing socket but to abnormally permit rotary movement of said plug to 125 register with the other casing socket; and, a 130

guard rotary plug having a keyway, a pin tumbler socket and a pin tumbler constructed and arranged to control and operate said detent mechanism.

- 5 4. In a changeable key lock, the combination with a casing; of a main rotary plug, having a keyway and a pin tumbler socket; two pin tumbler sockets in said casing, arranged to respectively register with the 10 socket in said main plug in different rotary positions of the latter; pin tumblers including changeable unit sections in said sockets, all of the same length, whereby said lock is changeable to be operated by any one of a 15 plurality of keys having notches the depths of which bear aliquot relation to said changeable tumbler sections; detent mechanism arranged to normally prevent the opening movement of the slide bolt but ab- 20 normally permit such movement; and, a guard rotary plug having a keyway, a pin tumbler socket and a pin tumbler constructed and arranged to control and operate said detent mechanism.
- 25 5. In a lock, the combination with a main rotary plug having a keyway; of two independent series of pin tumblers common to said plug and arranged to respectively co-operate with a key inserted therein, in dif- 30 ferent rotary positions of said plug; detent mechanism arranged to limit the rotary movement of said plug to register with but one or both of said series of tumblers, in accordance with the position of said detent 35 mechanism; a guard rotary plug having a keyway and arranged to control said detent mechanism; and, a series of pin tumblers ar- 40 ranged to co-operate with a key inserted in said guard plug, to prevent and permit rotation of the latter.

6. In a lock, the combination with a main rotary plug having a keyway; of two independent tumblers common to said plug and arranged to respectively co-operate with a 45 key inserted therein, in different positions of said plug; detent mechanism arranged to limit the rotary movement of said plug to register with but one or both of said tumblers, in accordance with the position of 50 said detent mechanism; a guard rotary plug having a keyway and arranged to control said detent mechanism; and, a tumbler ar- 55 ranged to co-operate with a key inserted in said guard plug, to prevent and permit rotation of the latter.

7. In a lock, the combination with a rotary plug having a keyway; of two independent tumblers common to said plug and arranged to respectively co-operate with a 60 key inserted therein, in different positions of said plug; detent mechanism arranged to limit the rotary movement of said plug to register with but one or both of said tumblers, in accordance with the position of said 65 detent mechanism; and, a guard tumbler ar-

ranged to co-operate with a guard key to control said detent mechanism.

8. In a changeable key lock, the combination with a main rotary plug, having a keyway and a radial pin tumbler socket; of a 70 casing having two radial pin tumbler sockets, arranged to respectively register with the socket in said plug in different rotary positions of the latter; pin tumblers including changeable unit sections in said sockets; springs thrusting said tumblers toward said plug; pivoted detent mechanism arranged to limit the rotary movement of said plug to register with but one or both of said casing 75 sockets; a guard rotary plug, having a keyway and a radial pin tumbler socket; and, a pin tumbler in said guard plug socket ar- 80 ranged to co-operate with a key to prevent and permit the rotation of said guard plug and operation of said detent mechanism.

9. In a changeable key lock, the combination with a main rotary plug, having a keyway and a radial pin tumbler socket; of a 85 casing having two radial pin tumbler sockets, arranged to respectively register with the socket in said plug in different rotary positions of the latter; pin tumblers including changeable unit sections in said sockets; springs thrusting said tumblers toward said plug; detent mechanism arranged to limit the rotary movement of said plug to register with but one or both of said casing 90 sockets; a guard rotary plug, having a keyway and a radial pin tumbler socket; and, a pin tumbler in said guard plug socket arranged to 95 co-operate with a key to prevent and permit the rotation of said guard plug and operation of said detent mechanism.

10. In a changeable key lock, a main rotary plug having a keyway and a tumbler 105 changeable to be operated by different keys; a slide bolt; pivoted detent mechanism ar- 110 ranged to normally prevent opening movement of said bolt; and, a guard rotary plug having a keyway and a tumbler arranged to co-operate with a key to control said detent mechanism.

11. In a changeable key lock, a main rotary plug having a keyway and a tumbler changeable to be operated by different keys; a slide bolt; detent mechanism arranged to normally prevent opening movement of said bolt; and, a guard rotary plug having a keyway and a tumbler arranged to co-operate with a key to control said detent mechanism. 120

12. In a changeable key lock, a main rotary plug having a keyway and a tumbler changeable to be operated by different keys; a slide bolt; detent mechanism including means arranged to normally prevent opening movement of said bolt and means ar- 125 ranged to normally prevent changes in said tumbler; and, a guard rotary plug having a keyway and a tumbler arranged to co-operate with a key to control said detent 130

mechanism arranged to normally prevent opening movement of said bolt, and, arranged to coöperate with another key to control said detent mechanism arranged to normally prevent changes in said tumbler; whereby, either of said detent mechanisms may be operated independently of the other.

13. In a changeable key lock, a tumbler changeable to be operated by different keys; 10 a slide bolt; detent mechanism including means arranged to normally prevent opening movement of said bolt and means arranged to normally prevent changes in said tumbler; and, a guard rotary plug having a keyway and a tumbler arranged to coöperate with a key to control said detent mechanism arranged to normally prevent opening movement of said bolt, and, arranged to coöperate with another key to control said 15 detent mechanism arranged to normally prevent changes in said tumbler; whereby, either of said detent mechanisms may be operated independently of the other.

14. In a changeable key lock, a tumbler changeable to be operated by different keys; 25 a slide bolt; detent mechanism including means arranged to normally prevent opening movement of said bolt and means arranged to normally prevent changes in said tumbler; and, a guard tumbler arranged to coöperate with a key to control said detent mechanism arranged to normally prevent opening movement of said bolt, and, arranged to coöperate with another key to control said 30 detent mechanism arranged to normally prevent changes in said tumbler; whereby, either of said detent mechanisms may be operated independently of the other.

15. In a lock, the combination with a 40 casing; of a slide bolt; detent mechanism arranged to normally limit the movement of said bolt; a rotary plug having a keyway, a plurality of tumbler sockets each having a peripheral recess extending circumferentially 45 at one side thereof, said recesses of different sockets extending in respectively opposite directions; tumblers in said casing engaging the respective plug sockets to the depth of the respective recesses; whereby, rotation of said plug is prevented by said tumblers; a key arranged to fit in said keyway and shift such tumblers out of engagement with said plug as to permit rotation of the latter in one direction; another key arranged to 50 fit in said keyway and shift such tumblers out of engagement with said plug as to permit rotation of the latter in the opposite direction; and, a master key arranged to fit in said keyway and shift such tumblers out 55 of engagement with said plug as to permit rotation of the latter in either direction.

16. In a lock, the combination with a 60 casing; of a slide bolt; detent mechanism arranged to normally limit the movement of said bolt; a rotary plug having a keyway, a 65

plurality of tumbler sockets each having a peripheral recess extending circumferentially at one side thereof, said recesses of different sockets extending in respectively opposite directions; tumblers in said casing engaging the respective plug sockets to the depth of the respective recesses; whereby, rotation of said plug is prevented by said tumblers; a key arranged to fit in said keyway and shift such tumblers out of engagement with said plug as to permit rotation of the latter 70 in one direction; and, another key arranged to fit in said keyway and shift such tumblers out of engagement with said plug as to permit rotation of the latter 75 in the opposite direction.

17. In a lock, the combination with a casing; of a slide bolt; detent mechanism arranged to normally limit the movement of said bolt; a rotary plug having a keyway, 80 a plurality of tumbler sockets each having a peripheral recess extending circumferentially at one side thereof, said recesses of different sockets extending in respectively opposite directions; tumblers in said casing 85 engaging the respective plug sockets to the depth of the respective recesses; whereby, rotation of said plug is prevented by said tumblers; and, a key arranged to fit in said keyway and shift such tumblers out of engagement with said plug as to permit rotation of the latter 90 in one direction.

18. In a lock, the combination with a casing; of a slide bolt; detent mechanism arranged to normally limit the movement of 100 said bolt; a rotary plug having a keyway, a tumbler socket, and a peripheral recess extending circumferentially at one side of said socket; a tumbler in said casing engaging said plug to the depth of said recess; whereby, rotation of said plug in one direction is prevented by said tumbler; and, a key arranged to fit in said keyway, shift said tumbler out of engagement with said plug and permit rotation of the latter in a direction 105 opposite to said recess.

19. In a lock, the combination with a casing; of a slide bolt; detent mechanism arranged to normally limit the movement of said bolt; a movable member having a keyway, a tumbler socket, and a recess extending at one side of said socket; a tumbler in said casing engaging said plug to the depth of said recess; whereby, movement of said member in one direction is prevented 115 by said tumbler; and, a key arranged to fit in said keyway, shift said tumbler out of engagement with said member and permit movement of the latter in a direction opposite to said recess.

20. In a lock, the combination with a casing; of a rotary plug having a keyway, a tumbler socket, and a peripheral recess extending circumferentially at one side of said socket; a tumbler in said casing engaging 120

said plug to the depth of said recess; whereby, rotation of said plug in one direction is prevented by said tumbler; and, a key arranged to fit in said keyway, shift said tumbler out of engagement with said plug and permit rotation of the latter in the direction opposite to said recess.

21. In a lock, the combination with a slide bolt; of detent mechanism arranged to normally limit the movement of said bolt; a guard rotary plug having a keyway, a tumbler socket, and a peripheral recess extending circumferentially at one side of said

socket; a tumbler engaged in said socket to the depth of said recess; whereby, rotation of said plug in one direction is prevented by said tumbler; and, a key arranged to fit in said keyway and release said tumbler.

In testimony whereof, I have hereunto, signed my name at York, Pennsylvania, this 20 seventeenth day of October, 1910.

WALTER REES.

Witnesses:

CHAS. W. ROLLE,
JAMES P. PARKER.

Correction in Letters Patent No. 1,004,904.

It is hereby certified that in Letters Patent No. 1,004,904, granted October 3, 1911, upon the application of Walter Rees, of York, Pennsylvania, for an improvement in "Changeable Key-Locks" an error appears in the printed specification requiring correction as follows: Page 1, line 84, for the word "guide" read *guard*; and that the said Letters Patent should be read with this correction therein that the same may conform to the record of the case in the Patent Office.

Signed and sealed this 24th day of October, A. D., 1911.

[SEAL.]

E. B. MOORE,
Commissioner of Patents.

said plug to the depth of said recess; whereby, rotation of said plug in one direction is prevented by said tumbler; and, a key arranged to fit in said keyway, shift said tumbler out of engagement with said plug and permit rotation of the latter in the direction opposite to said recess.
